(57) CLAIM

The ornamental design for a stylus, as shown and described.

DESCRIPTION

FIG. 1 is a perspective view of the stylus according to our new design;

FIG. 2 is a side view thereof;

FIG. 3 is a bottom view thereof;

FIG. 4 is an end view as seen from the left side in FIG. 2; and,
FIG. 5 is an end view as seen from the right side in FIG. 2.
The broken lines shown in the drawing are for illustrative purposes only and form no part of the claimed design.
